L. BROWN ET AL

PEAT FUEL PRODUCTION

Filed Sept. 20, 1924

By

LEONARD BROWN.
WALTER L. BROWN.

S. S. Brown,
Attorney

UNITED STATES PATENT OFFICE.

LEONARD BROWN AND WALTER L. BROWN, OF PROCTOR, MINNESOTA.

PEAT-FUEL PRODUCTION.

Application filed September 20, 1924. Serial No. 738,789.

This invention relates to peat fuel and and especially to the handling and preparation of same in the production of a commercial product.

5 The principal object is to provide an economical and practical method of transforming peat, as found in its natural state, to a commercial fuel.

Another object is to economize in the use 10 of fuel for drying purposes.

Still other objects and advantages will appear in the further description of the invention.

The accompanying drawing, forming part 15 of this application, in which like reference characters indicate like parts; represents, in a diagrammatical way, one embodiment of the invention, the same being partly in section and partly broken away.

20 In carrying out the invention we employ a heating furnace, indicated at 1, the combustion chamber being shown at 2, the same being fed by a suitable form of dust fuel such as pulverized coal, or, if desired, portions of the product resulting from the employment of the invention may be used, the fuel being fed through the pipe 3 and nozzle 4, which latter projects within the combustion chamber, and common in the art.

25 As a means of draft for the combustion chamber 1 we provide a pipe 5 having installed therein the suction fan or blower 6 operated by a suitable motor indicated at 7, the discharge from said fan being indicated 30 at 8 entering the upright storage bin or tank 9.

35 Intermediate of the fan or blower 6 and the combustion chamber 2 is installed a branch pipe 10 leading from the hopper 11 of a suitable macerator 12, into which de-watered peat may be fed by the endless belt or other means as indicated at 13.

40 A screw feed indicated at 14 is installed within the branch pipe 10 and operated in any desired manner as by the belt 15 on the pulleyed shaft 16, so that a constant supply 45 of finely powdered or macerated peat may be fed to the pipe 5 and subsequently into the blower 6 where it is conveyed with the resultant products of combustion from the 50 chamber 2 into the storage receptacle or depository 9.

We have indicated a screen or baffle, which

may be of any desired construction, at 17, in the extreme end of the combustion chamber 55 from the nozzle 4 for the separation of the sparks or heavy granular material that might occur within the combustion chamber so that the same may not be carried through into the fan 6, though it is evident that this may be 60 dispensed with or varied in respect to the fuel being used, and the latter may be any of various forms of gas or oil if so desired.

The storage tank or depository 9 is provided with an upright stack 18 through 65 which any remaining dampness or unutilized smoke or gas may be discharged, or, if considerable heat is found to escape from said discharge under certain conditions the same may be used over again in the further dry- 70 ing of subsequently treated peat.

We do not consider it essential in the disclosure of this invention to describe the manner in which the peat is originally treated or dewatered, as the same is immaterial and 75 it is well known that various methods of such accomplishment are resorted to; in fact, in many instances, peat is found in quite granular and more or less dried form which may be fed directly to the macerator 12. 80

Our present invention resides particularly in the passing of finely granulated peat and hot air through a fan and thence to a place of deposit for a final drying of the peat to a proper state for fuel purposes, together with 85 the novel arrangement for utilizing all of the heat and other products of combustion during such process of finally drying the peat.

It is to be noted that by passing granular 90 fuel substances through a fan and thoroughly commingling same with the products of combustion of a foreign fuel which may give off more or less unconsumed products, the latter may become incorporated 95 with the peat and thus saved for future consumption.

Having thus described our invention, what we claim and desire to secure by Letters Patent, is:

1. A peat drying unit of the character described comprising a combustion chamber, a depository located remote from the combustion chamber, a fan intermediate of the combustion chamber and the depository for conveying the products of combustion from the 100 105

former to the latter, and means for supplying dewatered granular peat to the products of combustion en route to the depository.

2. A peat drying unit of the character described comprising a combustion chamber, a depository located remote from said chamber, means intermediate of said chamber and the depository for forcibly conveying

the products of combustion from the former to the latter, and means for supplying dewatered granular peat to the products of combustion en route to the depository. 10

In testimony whereof we hereunto affix our signatures.

LEONARD BROWN.
WALTER L. BROWN.
